KANSAS, ASSIGNORS TO GENERAL ELECTRIC COMPANY, A CORPORATION OF
NEW YORK.

ELECTRIC LAMP FOR PROJECTION APPARATUS.

1,357,724.

Specification of Letters Patent.

Patented Nov. 2, 1920.

Application filed January 15, 1917. Serial No. 142,373.

To all whom it may concern:

Be it known that we, JOHN E. RANDALL, a citizen of the United States, residing at Cleveland, Cuyahoga county, Ohio, and LEROY T. RESER, a citizen of the United States, residing at Baldwin, Douglas county, Kansas, have invented new and useful Improvements in Electric Lamps for Projection Apparatus, of which the following is a specification.

Our invention relates to projection apparatus of various kinds including stereopticon, flood lighting and moving picture reproduction apparatus and more especially to an electric incandescent filament lamp particularly adapted for use with such apparatus.

One object of our invention is a lamp which will give a beam of light uniform throughout its depth. Another object is a lamp whose intrinsic brilliancy is greater than that of prior lamps having equal power consumption and the same operating temperature. Further objects are the elimination of local heating and arcing in the filament coils, and the simplification of the lamp and other parts of the projection apparatus whereby focal and other adjustments may be made with ease and certainty.

While the advantages of our novel lamp make it adaptable, to various applications, its greatest usefulness is found in connection with projection apparatus, and in the present case we have set forth the application to moving picture reproduction apparatus.

The incandescent filament lamp, as hitherto known, has not been particularly adapted for use as a source of light in moving picture projection apparatus, due among other things, to lack of intensity and lack of uniformity in light production throughout the filament area. Of the commercial lamps in use the gas filled tungsten lamp may be operated at the highest known temperature and efficiency, but prior lamps of this type have certain disadvantages when used in applications of this kind. For instance, the light production and emission are non-uniform in character and to obviate the objection the filament has been arranged in grid form, the sections being connected in series. This grid arrangement, while an improvement, failed to entirely remove this diffi-

culty and in order to further increase the uniformity in light production and distribution, it has been proposed to employ a reflector or mirror (spherical), located back of the lamp, for projecting an image of the filament adjacent thereto and within the filament plane, thereby bridging the gaps between adjacent sections of the series-connected filaments and practically doubling the area of the light source. We have found this arrangement to be objectionable from an operative standpoint on account of the difficulties in making accurate adjustments of the lamp with reference to the mirror and lenses. Moreover the reflected image is less intense than the original light source and this gives rise to uneven illumination on the screen. For instance, the intensity of the light issuing from the reflected image has been found to be approximately only 40% of the intensity of light issuing from the original light source. Furthermore I have found that the life of the lamp is shortened and its operation impaired when the mirror or reflector is used. This is probably due to aggravated local heating of the filament brought about by the presence of the mirror or reflector. Moreover the series-connected and grid formed filaments of the prior art have a tendency to arc across from one filament to the other, oftentimes before the lamp has had a reasonably long useful life, the arcing being aggravated by the high temperature at which the filament is operated. Furthermore, the potential difference between the coils in adjacent filament sections probably give rise to discharge or cross currents between these adjacent coils which are thought to cause a gradual impairment of the filament by the evaporation of the tungsten at certain points of the filament. These discharge currents are probably increased and the consequent deterioration of the filament is aggravated by the high temperature and high efficiency at which the filament must be operated to give the required illumination intensity. All of these causes contribute to premature termination of the useful life of the series-connected and grid-formed filament lamps.

In accordance with our invention we reduce to a minimum or entirely remove these causes (for premature termination of the

useful life and we do away altogether with the necessity of a reflector or mirror for increasing the intensity and the uniformity of the light beam, thereby saving the expense 5 of reflector installation and avoiding the troubles incident to its operation, and we accomplish this by a novel form of monoplane incandescent lamp, which gives a highly intense and uniform beam of light 10 and whose life is not unduly impaired by arcing and cross currents and by its high temperature in operation. Our improved lamp embodies more specifically a multiplicity of coiled or spiral filaments connected in multiple and these filaments are mounted close together in panel form on two rigid electro-conductive posts or supports, the filament sections and the supports being easily disposed and assembled in a monoplane 15 position. With the multiple connection the adjacent coils on the different filaments are at the same potential and consequently there is no tendency to arc across from one filament to another and moreover 20 the discharge or cross currents which are thought to attack the tungsten filament are reduced to a minimum. The filaments may, therefore, be brought close together, or even crowded together to form a true ribbon 25 filament which gives a highly intense and uniform light beam throughout its area. We have found too that the intrinsic brilliancy of the parallel connected coils disposed closely together is substantially 30 greater than that of the series-connected and grid-formed filaments of the prior art, giving the appearance of a higher temperature, although the power consumption in the two cases is the same. By this higher 35 intrinsic brilliancy the illumination efficiency is greatly enhanced. This higher brilliancy is probably due to radiation added by reflections between the filaments.

Another important feature of our invention 40 is that by concentrating the filament sections the whole plane of the filaments may be brought within the field of the screen illumination, thereby making use of every turn of the filament sections to furnish useful light. With the old series-connected filaments such concentration was impossible and consequently a lamp embodying an equal number of filament turns very often could not be brought wholly within 45 the field, certain portions of the area of the plane of the filaments being entirely outside thereof and the light therefrom consequently wasted. It is understood in all kinds of projection apparatus only a certain 50 field or screen area is required to be illuminated, this being particularly true of moving picture reproduction apparatus where standardization has been pretty generally accomplished.

60 65 Another important feature of our invention

resides in the avoidance of certain difficulties experienced in making accurate focal adjustments with the lamps of the prior art. We have found these difficulties to be due in part to the displacement of the 70 filament sections out of the monoplane position. This displacement may be due either to inaccurate adjustments in the manufacture or to subsequent distortion and sagging in the operation of the lamp. The displacement during the manufacture of the prior lamps was the result of difficulties experienced in accurately maintaining a monoplane position while shaping the filament into grid form and also while adjusting the multiplicity of supports necessary 75 in this type of lamp. By mounting the filaments in panel form between the two posts or supports the positioning of the filaments in a monoplane position becomes a simple 80 matter, as will hereafter more particularly appear. The distortion of the filament out of the monoplane position may be due to the twisting of the coil filaments under the influence of the intense heat of the lamp. 90 We have found, however, that all displacement due to distortion or sagging may be obviated by accurately predetermining the maximum length of the filaments for certain wire and coil diameters and rigidly 95 supporting these filament sections from their ends, as, for instance, mounting them on the parallel disposed rigid electro-conductive posts. For instance, with a wire diameter of .0195 inches and a coil diameter 100 of approximately .08 inches, we have found that a filament section one-half inch long from end coil to end coil is maintained in the monoplane position at all times and no appreciable distortion or sagging takes 105 place in the operation, notwithstanding the intense heat of the filament. The length of the filament may be increased by 25 to 50% without unduly increasing the sagging or distortion.

110 The above features set forth as characterizing our novel lamp make it particularly adaptable for use in moving picture reproduction apparatus. For instance, with the filament lengths closely coiled and assembled together as above noted, the light emitted is substantially uniform throughout the depth of the beam and the curve of distribution approximates that of a solid band of light. Assuming an optical system is 115 employed which transmits to the screen the light flux within a solid angle of 110 degrees, approximately 25% of the total light emitted by the source is useful in lighting the 120 screen, which compares favorably with the calculated 30 to 33% useful light expected from a solid band source of the same monoplane area, the useful light in the latter case being dependent on the thickness of 125 the assumed band of tungsten. The 33% 130

useful light would be expected if no thickness is assumed, and the 25% useful light is obtained with four coils arranged in multiple, the coils being .08 inch in diameter and $5\frac{1}{2}$ inch long. The closely coiled filaments should be concentrated into a monoplane area of considerably less than five tenths of a square inch to obtain the best efficiency with moving picture apparatus now in use 10 and the best results are obtained when the concentration is such that the length of the monoplane area is less than twice the breadth. For example, with four filament lengths of the above noted dimensions, 15 closely coiled (turns separated by approximately one thirty second of an inch) and assembled together in a monoplane area of approximately sixteen one hundredths of a square inch (five tenths of an inch long by 20 thirty-two one hundredths inches wide) and with a calculated operating temperature of approximately 3275 degrees K (absolute), a spherical candle power of 1950 or greater has been obtained and the intensity at right 25 angles to the plane of the source has reached 3350 candle power, and tests have shown a uniform intensity of six to ten foot candles on a screen at an eighty foot throw, these results being obtained without the use of a 30 mirror or reflector. The tests were made on lamps operating at approximately 12 volts and at an overall efficiency greater than one-half watt per candle, the leading-in wire and terminal heat losses being ignored 35 in the efficiency calculation.

For a better understanding of our invention reference may be had to the drawings accompanying this specification which are 40 illustrative of certain of the many forms our invention is capable of assuming.

Referring to the drawings, Figure 1 is a side view of a lamp complete; Fig. 2 shows a slightly modified construction of filament and supports; Fig. 3 shows a diagrammatic 45 illustration of the lamp and moving picture apparatus; and Fig. 4 is a partial elevation of another modifying construction of the filament.

The preferred construction is shown in 50 Fig. 1 where the usual inclosing bulb 1 is used to house the lamp filament and leading-in wires and supports. The supports 2 which may be of nickel or other metals extend upwardly from the stem and carry the 55 coiled filaments 3. The latter are preferably carried on auxiliary supports 4, as of tungsten or molybdenum, which are securely fastened to the lower supports in any convenient manner, as by welding. The filaments 3 may be easily and quickly secured to the supports by forming electrical welds between the filament ends and the posts 4. 60 The auxiliary supports or posts 4 and filaments 3 may be assembled and mounted as 65 a unit on supports 2, or the posts 4 may be

accurately mounted and positioned in the same plane without the exercise of great care, and the filaments subsequently mounted. A convenient way of mounting the filaments is to assemble the filaments between 70 suitable clamps and in a monoplane position and then, causing the filaments so assembled to bridge the supports 4, securely weld the free ends to the posts by resistance or arc welds. The supports should be of large and 75 substantial dimensions as compared with the filaments, that is, they should have such a rigidity as not to yield to any strain of the filaments during the operation. The rigidity and strength of the supports combined 80 with the comparatively short filaments (length $\frac{1}{2}$ inch, wire diameter .0195 and coil diameter .08 inch) avoid any harmful displacement during the normal life of the 85 lamps and this renders the making of focal adjustments a simple and more certain matter. The filament 3, as shown in the drawings, may be actually crowded together without causing any inconvenience from arcing, the coils of adjacent filaments being substantially at the same potential. Each filament in the embodiment shown takes approximately 20 amperes running at 12 volts across the lamp terminals and at this efficiency the life is from 100 to 150 hours. 90

Fig. 2 shows a construction wherein the filaments are arranged at right angles to the position illustrated in Fig. 1, the construction otherwise being substantially the same. 100

In Fig. 3 the lamp is illustrated in connection with moving picture apparatus, wherein are shown a condensing lens 5, an objective 6, film 7 and screen 8. The usual mirror or reflector is entirely done away 105 with, and the installation expense is thereby saved. Moreover, the necessary accurate adjustments accompanying the mirror are entirely obviated, and the harmful results on the life of the lamp are eliminated. 110

What we claim as new and desire to secure by Letters Patent of the United States is:

1. An electric incandescent lamp comprising a plurality of closely coiled filaments of uniform cross section disposed closely together and connected in multiple, the distance between adjacent filaments being substantially less than the diameter of the filament coil. 115

2. An electric incandescent lamp comprising a multiplicity of coiled filaments of uniform cross section arranged parallel to each other in a plane and electrically connected in multiple, the distance between adjacent filaments being substantially less than the diameter of the filament coil. 125

3. An electric incandescent lamp comprising a multiplicity of closely coiled filaments of uniform cross section arranged in a plane 130

- parallel to each other and electrically connected in multiple, the distance between adjacent filaments being substantially less than the diameter of the filament coil.

5. An electric incandescent lamp comprising two or more coiled filaments of uniform cross section disposed closely together in one plane and electrically connected in parallel, the distance between adjacent filaments being substantially less than the diameter of the filament coil.

10. An electric incandescent lamp comprising two or more closely coiled filaments of uniform cross section arranged parallel to each other and disposed closely together in one plane, said filaments also being electrically connected in multiple, the distance between adjacent filaments being substantially less than the diameter of the filament coil.

15. An electric incandescent lamp comprising a multiplicity of coiled filaments of uniform cross section carried and supported at their ends by two parallel and electro-conductive posts, the distance between adjacent filaments being substantially less than the diameter of the filament coil.

20. An electric incandescent lamp comprising a multiplicity of coiled filaments of uniform cross section carried and supported at their ends by two parallel and electro-conductive posts, the distance between adjacent filaments being substantially less than the diameter of the filament coil.

25. An electric incandescent lamp particularly adapted for use in projection apparatus comprising two rigid electro-conductive posts mounted upon the stem and a multiplicity of closely coiled filaments of uniform cross section bridging said posts and disposed closely together in one plane, the distance between adjacent filaments being substantially less than the diameter of the filament coil.

30. An electric incandescent lamp particularly adapted for use in projection apparatus comprising two rigid electro-conductive posts parallel arranged and mounted upon the stem and multiplicity of closely coiled filaments of uniform cross section bridging said posts and disposed closely together, the distance between adjacent filaments being substantially less than the diameter of the filament coil.

35. An electric incandescent lamp particularly adapted for use in projection apparatus comprising a plurality of closely coiled metal filaments of uniform cross section connected in parallel and disposed substantially in a single plane and operating at an efficiency greater than one-half watt per candle power, the distance between adjacent filaments being substantially less than the diameter of the filament coil.

40. An electric incandescent lamp for projection purposes comprising a plurality of closely coiled metal filaments of uniform cross section electrically and geometrically connected in parallel and concentrated into a monoplane area of less than half a square inch, the length of said monoplane area being less than twice its breadth, the distance between adjacent filaments being substantially less than the diameter of the filament coil.

45. An electric incandescent lamp for projection purposes comprising a plurality of coiled metal filaments of uniform cross section electrically connected in parallel and operating at a temperature which gives an efficiency greater than one-half watt per candle, said filaments being concentrated to such extent and into a volume of such contour that the light flux is substantially uniform throughout the depth of the beam and the curve of distribution approximates the curve of distribution of a solid band of light, the distance between adjacent filaments being substantially less than the diameter of the filament coil.

50. In an electric incandescent projection lamp, a filament comprising a plurality of parallel closely wound coils connected electrically in multiple and disposed in the same plane, the spaces between the said coils being materially less than the width or diameter of the said coils.

55. In witness whereof the said RANDALL has hereunto set his hand this 10th day of January, 1917, and the said RESER has hereunto set his hand this 6th day of January, 1917.

JOHN E. RANDALL.
LEROY T. RESER.

In witness whereof the said RANDALL has hereunto set his hand this 10th day of January, 1917, and the said RESER has hereunto set his hand this 6th day of January, 1917.

JOHN E. RANDALL.
LEROY T. RESER.
